PILE FABRIC

Alfred Wright, Philadelphia, Pa., assignor to J.
Harris Warthman, trustee

Application April 22, 1937, Serial No. 138,447

4 Claims. (Cl. 26—69)

This invention relates to pile fabrics and more especially to those adapted for use in upholstery, as coverings for soft overstuffed furniture, table and other hard surface covers, draperies, etc. 5 The present invention relates more particularly to textile fabrics of the velour, velvet, or other types which normally have a pile nap lying smoothly in one direction only, over the entire area of fabrics having no design configuration formed therein or over the background portions, at least, of figured fabrics, which gives the fabric a general uniformly sleek appearance.

The object of the present invention is to disturb the normally uniform sleek appearance of 15 the pile face of the fabric, by introducing therein an effect which somewhat resembles ripples on a normally smooth surface of a quiescent body of liquid produced by localized agitation, which causes the ripples to form in substantially parallel and angularly intersecting irregular lines, which produces a shimmering effect as the ripples catch and reflect rays of light.

Fabrics made in accordance with the principles 25 of the present invention, with materials having a certain amount of sheen, depict a shimmering ripple effect similar to that above noted.

In the accompanying drawing:

Fig. 1 diagrammatically illustrates a swatch of 30 figured fabric having a ripple background produced in accordance with the principles of the present invention;

Fig. 2 illustrates an all-over ripple effect;

Fig. 3 diagrammatically illustrates one step in 35 the production of the ripple effect; and

Fig. 4 illustrates a second step in the production of the ripple effect.

As far as the present invention is concerned, it 40 matters not whether the fabric be woven single or double, or what the construction of the base fabric 1 may be, or how the pile-forming threads or filaments 2 are tied into the base fabric 1.

Normally pile fabrics of the type involved in 45 the present case, after being woven, are subjected to a finishing process which may include piece-dyeing, etc. but which in any event involves a thorough wetting of the material. While wet, the pile face of the fabric is normally brushed, in one direction only, an operation which is commonly referred to in the art as "tigering" and 50 which causes the pile threads 2 to lie or point all in one direction, giving a unidirectional lay to the pile nap.

The angle at which the tigered pile threads 2 project from the plane of the base fabric 1 depends, to some extent at least, on the materials 55

of which the pile threads 2 are composed. For example, pile threads composed of yarn made up of continuous filaments, such as natural or artificial silk, have a tendency to be stiffer than threads composed of cotton or silk (natural or artificial) fibers or filaments of various lengths spun or twisted together to produce the pile-forming threads.

Spun fiber threads have a softer texture than continuous filaments threads. Consequently, pile 10 threads 2 when formed of continuous filament yarn will inherently rise to a greater extent or greater angle from the plane of the base fabric 1, after the wet brushing and subsequent drying, than will the threads when composed of the 15 spun yarn.

As a result of the above noted difference in angle the stiffer pile threads will stand practically perpendicular to the plane of the base fabric 1, which will present the cut ends of the stiff filaments to view, while the sides of the softer threads will be presented to view. Thus, in the one case, looking at the ends of the threads gives a relatively dull effect while looking at the sides of the 20 softer threads, particularly when such threads 25 are composed of material having a sheen, gives a bright lustrous effect, as a result of the sides of the softer threads reflecting light rays while the ends of the stiffer threads absorb the light rays.

Thus, in a figured fabric, wherein the figure is composed of continuous filament threads and the background is composed of soft spun fiber threads, the background will have a uniform sleek, bright, lustrous appearance while the figure 30 stands out prominently in dull contrast thereto, even in cases where the color shade is alike in both instances.

In fabrics having a pile face made of soft spun fibrous yarns throughout, the sleekness is uniform throughout the entire area of the fabric. In this case, a design may be produced by using a soft spun yarn of one kind for a figure, for example cotton, and a soft spun yarn of a different kind, for example silk, for the background, 45 which, during subsequent piece-dyeing, will take the dye to different degrees and present a pattern in a different shade but of the same color as the background of said figure.

The present invention concerns the disturbance 50 of the above noted general uniform sleekness of the fabric, primarily by breaking up the solid light-reflecting areas of the pile face of the fabric. This is accomplished by raising pile threads haphazardly, in irregular lines which extend in 55

one general direction transversely of the fabric but which lie at slight angles to each other in some places, substantially parallel to each other in other places, and here and there intersect each other, which collectively produce a general ripple effect, by presenting the light-absorbing ends of the pile threads at those places where the pile threads are raised and the side light-reflecting surfaces of the pile threads which are left lying in the normal position of the nap where the pile threads are not raised.

In a fabric having the pile face composed throughout of spun fibers the ripple effect will be an all-over affair, whereas in a fabric having a design formed of continuous filament threads the design will stand out prominently while the ripple effect will extend throughout the background areas.

Fig. 1 illustrates a fabric wherein the ends of stiffer continuous filament pile threads depict a design 3 on a background 4 composed of spun yarn, wherein certain of the previously laid pile threads 2 have been raised haphazardly to expose the light-absorbing ends of the spun threads, as illustrated at 5, while the light-reflecting sides of the non-raised threads, shown at 6, are interspersed throughout the whole of the pile surface of the background 4 and reflect the light rays in the form of the shimmering ripple effect above noted.

In Fig. 2, the pile face of the fabric is shown as being composed exclusively of spun yarn with the light-absorbing ends of the raised pile threads 2 showing at the places designated 5 and the light-reflecting sides of the non-raised threads 2 showing at the places designated 6.

Fig. 3 shows the first step of producing the finish desired, wherein the base fabric 1 is moving in the direction of the arrow *a* and the pile threads 2 are being brushed all in one direction by a revolving bristle brush 7 rotating in the direction of the arrow *b*, that is, in the direction of movement of the fabric 1, and by which the pile threads 2 are laid all in one direction, as illustrated at 2a. This is the normal step of laying the nap in fabrics as produced heretofore.

Fig. 4 illustrates the fabric moving in the direction of the arrows *a*¹ and *a*² over and around a relatively acute edge 8 of a blade 9, with a bristle brush 10 spaced from said edge and revolving in the direction of the arrow *b*¹, that is, a direction opposite to the direction of movement of the fabric.

The brush 10 is set in such relation to the fabric that the previously laid threads 2a can pass between the periphery of the brush and the blade edge 8 without being engaged by the brush. However, when the fabric is bent sharply in passing around the edge 8, the wet threads 2a which have been previously brushed and laid flatly on the base fabric 1 and which, due to their wet condition have stuck to each other and to the base fabric, pull loose in groups at their outer or free ends, here and there across the fabric, as the fabric passes around the sharp edge 8. These threads in loosening, spring upwardly and are caught at their free ends by the reversely moving brush 10 which stands the threads up more or less erectly so that the ends of the loosened threads are presented to view amongst the threads which remain flat. This spontaneous and rather erratic loosening of scattered groups of the threads 2a passes from one line or course of the pile tufts, formed of the threads 2, into

following courses and this causes the irregular angular, parallel and intersecting ripple lines.

The formation of the irregular ripple lines is also effected more or less by the fact that the courses of pile tufts when passing around the acute edge 8 are not absolutely parallel with said edge at all times but waver back and forth across the edge 8 in a slightly irregular line which causes the laid threads 2a to spring upwardly in scattered groups instead of in full complete lines running straight across the fabric.

The threads 2 when wet and stuck down to the base of the fabric by the adhesiveness of the liquid by which the threads 2 are wetted causes the laid threads to be under a certain amount of surface tension and the bending of the fabric around the acute edge 8 with the courses of tufts slightly irregular with respect to the edge 8 breaks this surface tension in spots and releases groups of the threads which spring up into contact with the brush 10.

If desired, the peripheral surface of the brush 10 may be provided with irregularly or uniformly arranged low spots, deep enough below the high peripheral surface of the brush to miss the threads 2 at all times; and the brush may be arranged with the high surfaces of the brush in constant contact with the laid threads 2. Then, as the brush revolves, the high surfaces of its periphery will raise some of the threads 2 while the low spots in the surface of the brush will miss others of the laid threads 2. This form, however, is not preferred as it tends to make the ripples too uniform, whereas the preferred method, previously described, produces no regularity or repeat and adds beauty to the general ripple effect.

The primary "tigering" or brushing shown in Fig. 3 is normally done with the brush 7 composed of wire bristles, to produce a combing effect for separating the pile threads one from another and arranging them in substantially parallel relation to each other at the same time as the pile threads are collectively being laid all in one direction longitudinally of the fabric. However, animal or vegetable fiber bristles may be used if desired.

The secondary brushing in the reverse direction, by the brush 10 as shown in Fig. 4, is preferably accomplished by a brush composed of pig bristles or an equivalent therefor, as a combing effect is not so essential in this instance, but a wire bristle brush may be used if desired.

I claim:

1. The process of finishing a cut pile face of a textile fabric which includes wetting the threads of which the pile face is composed, laying said wet threads all in one direction over the pile face of the fabric, and bending said fabric at an angle to the normal plane of the fabric to cause groups of the wet laid threads to loosen and rise from the positions in which they had been previously laid.

2. The process of finishing a cut pile face of a textile fabric which includes wetting the threads of which the pile face is composed, laying said wet threads all in one direction over the pile face of the fabric, and bending said fabric at an angle to the normal plane of the fabric to cause groups of the wet laid threads to loosen and rise from the positions in which they had been previously laid and simultaneously there-with brushing the rising threads in a direction opposite to that in which said threads had been previously laid.

3. The process of finishing a cut pile face of a

textile fabric which includes wetting the threads of which the pile face is composed, brushing said wet threads all in one direction over the pile face of the fabric to cause said threads to lie substantially flat and parallel to the normal plane of the fabric and to adhere to the fabric and to each other, and bending said fabric at an angle to the normal plane of the fabric to cause groups of the wet laid threads to loosen and rise from the positions in which they had been previously laid.

4. The process of finishing a cut pile face of a textile fabric which includes wetting the threads

of which the pile face is composed, brushing said wet threads all in one direction over the pile face of the fabric to cause said threads to lie substantially flat and parallel to the normal plane of the fabric and to adhere to the fabric and to each other, and bending said fabric at an angle to the normal plane of the fabric to cause groups of the wet laid threads to loosen and rise from the positions in which they had been previously laid and simultaneously therewith brushing the rising threads in a direction opposite to that in which said threads had been previously laid.

ALFRED WRIGHT.
